COMBINATION SKI AND SNOWSHOE

Joseph A. Arsenault, Mexico, Maine

Application August 18, 1945, Serial No. 611,363

6 Claims. (Cl. 36—4.5)

1

This invention relates to skis and has for an object to provide a ski which may be quickly transformed into a snowshoe.

Another object of the invention is to provide in a ski hinged side wings which may be used as a snowshoe for hill climbing.

A further object of the invention is to provide a two-in-one combination of a ski and snowshoe.

Other features and advantages will become more readily apparent from the following description and the accompanying illustrative drawing in which:

Figure 1 is a plan view of my device as a snowshoe.

Figure 2 is a side elevational view thereof shown as a ski, and

Figure 3 is a view taken on line 3—3 of Figure 1.

In the accompanying drawing as above enumerated and in the following specification, like characters of reference indicate like parts throughout and in which 10, indicates my combination ski and snowshoe, 11 being the ski to the sides 12 and 13, of which are attached by hinges 14 and 15, snowshoe sections 16 and 17, which may be let down on a common plane with that of the ski or which may be held raised by means of straps 18 and 19. The ski is provided with the usual turned-up end 20, foot support 21, and foot strap 22. The strap 18, is secured to the outer frame 23, of the member 16, and a strap 19, is secured at 24, to the outer frame member 25, of the wing 17, and the straps are connected by a buckle 26, in order that the wings may be drawn up to vertical position and so fastened when the device is to be used as a ski.

However, when the device is to be used as a snowshoe the buckle 26, is to be loosened to allow the wings 16 and 17, to drop to a common horizontal plane with the ski member 12, and the centrally pivoted steel straps 27 and 28, are turned transversely of the ski, to engage both frame members, forwardly and rearwardly thereof and fastened down securely by the wing nuts 29 and 30, thus holding the members 16 and 17, in rigid horizontal position. When the device is used as a ski, the straps are pivoted to longitudinal positions on the ski, as indicated in dotted lines and the nuts tightened.

With my above described device hill climbing, moving over even slight inclines will be greatly facilitated as the user has the advantage of a snowshoe in walking up such inclines and is thus saved much exertion and fatigue.

With my ski-shoe combination a wearer will be

2

able to make much faster time in traveling over rough country than can possibly be done with either skis or snowshoes, as on level ground or going down inclines the ski alone may be used, but in climbing even slight inclines the combination can be used to great advantage and in going down a hill the man with only snowshoes would be left very far behind.

It is thought that persons skilled in the art to which the invention relates will be able to obtain a clear understanding of the invention after considering the description in connection with the drawing. Therefore, a more lengthy description is regarded as unnecessary.

15 Minor changes in shape, size and rearrangement of details and parts such as come within the purview of the invention claimed may be resorted to, in actual practice, if desired.

Having now described my invention that which 20 I claim as new and desire to procure by Letters Patent is:

1. In a device as described a ski and wings hingedly connected to the sides thereof, said wings being in the form of a longitudinal half 25 of a snowshoe, and means for holding the wings in raised position.

2. In a device as described a ski and wings hingedly connected to the sides thereof, and said wings being in the form of a longitudinal half 30 of a snowshoe.

3. A device as described including a ski, and wings hinged to each side thereof and pivotal means on the ski for holding the wings in horizontal position, said means consisting of rigid 35 straps adapted to overreach the outer edges of the wings, said wings being netted, and means for holding said straps parallel with the ski.

4. A device as described including a ski, and wings hinged to each side thereof and pivotal 40 means on the ski for holding the wings in horizontal position, said means consisting of rigid straps adapted to overreach the outer edges of the wings, and said wings being netted.

5. A device as described including a ski, and wings hinged to each side thereof and pivotal means on the ski for holding the wings in horizontal position, and said means consisting of rigid 45 straps adapted to overreach the outer edges of the wings.

6. A device as described including a ski, and wings hinged to each side thereof and pivotal means on the ski for holding the wings in horizontal position.

JOSEPH A. ARSENAULT.
